UNITED STATES PATENT OFFICE.

VICTOR E. EDWARDS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

ROLLING-MILL.

1,040,293.

Specification of Letters Patent.

Patented Oct. 8, 1912.

Application filed January 17, 1907. Serial No. 352,795.

To all whom it may concern:

Be it known that I, VICTOR E. EDWARDS, a citizen of the United States, residing at Worcester, in the county of Worcester and 5 Commonwealth of Massachusetts, have invented a new and useful Improvement in Rolling-Mills, of which the following is a specification, accompanied by drawings forming a part of the same, in which—

10 Figure 1 represents in plan view a rolling mill embodying my invention. Fig. 2 is a plan view of a portion of the rolling mill, showing a changed position of the trains of rolls from that represented in Fig. 1. Fig. 15 3 is a sectional view on a larger scale on line 3—3 Fig. 1, showing two trains of rolls in end elevation and Fig. 4 is a side elevation of one of the movable trains of rolls.

Similar reference letters and figures refer 20 to similar parts in the different views.

My present invention relates to a rolling mill for the continuous reduction of a metal bar, comprising a series of pairs of rolls each journaled in a roll housing and provided with channels or "repeaters" for conducting a metal bar from one pair of rolls to another consecutively, and my invention relates particularly to the finishing rolls of the series by which the exact dimensions 25 required are given to the finished product.

The object of my invention is to enable the product to be changed at will without necessitating a prolonged interruption of the operation of the mill, such as would be 30 required to change one or more pairs in their respective housings.

By my improvement I divide the rolls of the finishing mills into separate trains of rolls, with the roll housings of each train 35 40 of rolls mounted upon bases which are longitudinally movable on tracks or ways, and I provide duplicate trains of rolls, similarly mounted and movable longitudinally on contiguous parallel ways with actuating 45 mechanism for moving each of the duplicate trains of rolls into and out of operative position.

Referring to the accompanying drawings 1 denotes rolls for the initial reduction of a

heated billet as it is taken from the furnace 50 and the rolls 2 and 3 form what is known as the "finishing mill" in which a metal bar delivered from the rolls 1 is reduced to the required size and shape and delivered upon a cooling bed 4. The rolls 2 are journaled in pairs in housings 5 which are mounted upon a base 6 longitudinally movable on a track 7 and constituting a single train of rolls A which are capable of being moved into and out of operative position 55 on the track 7. The rolls 3, comprise the two last pair of rolls in the finishing mill and are journaled in housings 8 similarly supported on a base 9, constituting a train B capable of being moved on the track 7 60 in and out of operative position. The metal bar received from the rolls 1 is conducted through channels or repeaters in the usual manner from one pair of rolls to the next succeeding pair of rolls. The repeaters 65 comprise curved sections 10 supported upon the floor 11 of the mill and removable straight sections 12 connecting the curved sections with the passes of the rolls.

Adjacent to and parallel to the track 7 is 70 a similar track 13 and longitudinally movable thereon are the bases 14 and 15. On the base 14 are mounted roll housings 16 in which are journaled the rolls 17 constituting a single train C. On the base 15 are 75 mounted the roll housings 18 in which are journaled the rolls 19 constituting a single train D. The bases and housings of the trains C and D are a duplicate of those in trains A and B and as the trains C and D 80 are capable of being substituted for the trains A and B I term the former substitutional and the latter operative trains.

I do not confine myself to any particular means for rotating the rolls of the respective trains but I prefer to employ electric motors 20 mounted upon and movable with the bases of the several trains. I do not confine myself to any specific means for moving the trains longitudinally on the 85 tracks 7 and 13 but this may be conveniently accomplished, as shown in the accompanying drawings, by providing the

bases of the trains with nuts indicated by the broken lines 21 and engaging screws 22, 23, 24 and 25. The screws 22 and 23 are rotated simultaneously in opposite directions by right and left hand worm gear connections 26 and 27 with a shaft 28. The screws 24 and 25 are similarly rotated in opposite directions by right and left hand worm gear connections 26 and 27 with a shaft 29 and the shafts 28 and 29 are driven by motors 30. The tracks and the housings of the trains, for convenience, are depressed as shown in Fig. 3 in order to bring the passes in the horizontal plane of the curved sections 10 of the repeaters. In Fig. 1 the trains A and B are shown in operative position, but in case a change is desired in the shape or size, in cross section, of the finished product suitable rolls 19 therefor are installed in the train D without interrupting the operation of the rolls in train B. By simultaneously operating the screws 22 and 23 the trains B and D are moved in opposite directions on the tracks 7 and 13, moving the train B out of operative position and the train D into operative position as shown in Fig. 2, each train being moved as a unit. The removable straight sections of the repeaters, which are of different lengths on opposite sides of the rolls are transferred and the operation of the mill may be resumed with the trains A and D in operative position. In like manner the trains A and C may be shifted bodily on the tracks 7 and 13 by the rotation of the screws 24 and 25. The consecutive reduction of a metal bar therefore may be carried on through the joint operation of either trains A and B as shown in Fig. 1, of trains A and D, of trains C and B or trains C and D. Whenever any change of rolls becomes necessary in order to change the track or for other reasons such change can be made in the trains which are in inoperative position and the trains quickly shifted with but slight interruption in the operation of the mill.

In practice any slight changes in the shape or size of the product can be made by simply shifting the trains B and D thereby changing the two last pair of rolls in the mill. A division of the series of rolls forming the finishing mill may be made at any desired point in the reduction of a metal bar, but in practice I prefer to place the two last pairs of rolls in a single train.

I claim,

1. In a rolling mill, the combination with a series of pairs of rolls arranged for the reduction of a metal bar, of means for withdrawing a pair of rolls from said series, and means for guiding another pair of rolls into operative relation with said remaining rolls in said series.

2. In a rolling mill, the combination with a series of pairs of rolls arranged for the reduction of a metal bar, of means for withdrawing in a definite path a pair of rolls from said series, and means for the introduction in a definite path of another pair of rolls into similar operative relation with the remaining rolls of said series.

3. In a rolling mill, the combination with a series of pairs of rolls arranged for the reduction of a metal bar, of means for the withdrawal of a pair of rolls from operative relation with the remaining rolls of said series, and another pair of rolls arranged to be brought simultaneously into operative relation with the remaining rolls of said series.

4. In a rolling mill, the combination of a pair of parallel tracks, a train of rolls supported on each of said tracks and means for moving said trains on their respective tracks, whereby either of said trains is brought into or out of position for conjoint action with the remainder of the mill.

5. In a rolling mill, the combination with a pair of parallel tracks, of a train of rolls supported on each of said tracks, screws for moving said trains longitudinally on said tracks and means for simultaneously actuating said screws.

6. In a rolling mill, the combination with a series of sets of rolls arranged for the reduction of a metal bar, independent means for the rotation of each set of rolls, and a supporting base for each set of rolls and its means of rotation, of means for withdrawing a single supporting base to bring the supported set of rolls out of operative relation with the remaining sets of rolls, and means for introducing another base with its supported set of rolls into similar operative relation with the remaining sets of rolls.

7. In a rolling mill, the combination with a series of pairs of rolls arranged for the reduction of a metal bar, stationary ways or channels for conducting said metal bar from each pair of rolls in said series to the next succeeding pair of rolls, means for withdrawing a pair of rolls from said series, and means for guiding another pair of rolls into a position with relation to said ways corresponding to that occupied by said withdrawn pair of rolls.

8. In a rolling mill, the combination with a series of movable bases, each base arranged to support roll housings of reducing rolls journaled in said housings, a single horizontal track for said series of bases, and means for moving each of said bases on said track to bring the rolls on each base into and out of co-operative action for the reduction of a metal bar.

9. In a rolling mill, the combination with

a series of movable bases, each base arranged to support the housings of a pair of rolls, a single horizontal track for said bases, a duplicate series of bases and a horizontal track for said duplicate bases parallel with said first track, and means for moving each base on its track into and out of position for coöperative action for the reduction of a metal bar.

VICTOR E. EDWARDS.
